WITNESS:

Gerald Henney, Sr.

UNITED STATES PATENT OFFICE.

FAY L. KUELLMER, OF DENVER, COLORADO.

ELASTIC THREADING AND FASTENING DEVICE.

Application filed January 13, 1925. Serial No. 2,220.

To all whom it may concern:

Be it known that I, FAY L. KUELLMER, a citizen of the United States, residing at Denver, in the county of Denver and State 5 of Colorado, have invented new and useful Improvements in Elastic Threading and Fastening Devices, of which the following is a specification.

This invention relates to accessories used 10 in connection with garments of various kinds and has for its object the provision of a novel device designed to be secured upon the ends of a suitable length of elastic whereby to facilitate threading the elastic 15 through the hem of a garment when initial application is made, the device further including two parts adapted to be connected together subsequent to the threading of the elastic into place whereby to hold the 20 elastic in embracing relation to the body or limb encircled thereby and positively prevent accidental displacement.

It is well known that very many articles 25 of apparel worn by women, children and others contain a band or strip of elastic which, in some instances, is intended to be engaged about the waist, and which, in certain other instances, is intended to engage about the leg or possibly the arm. It is 30 a matter of common knowledge that the elastic very shortly becomes useless on account of the natural deterioration of the rubber and it then becomes necessary to replace the worn out elastic with a new strip.

35 Under the ordinary practice it is necessary to make use of a bodkin, safety pin or the like in threading through a new strip and it is afterwards necessary to sew the ends together to make the proper connection.

40 It is with the above facts in view that I have designed the present invention which has for a more specific object the provision of a fastening device including separable elements, one of which is capable of employment in lieu of a bodkin or the like in threading a new piece of elastic in place.

An additional object is the provision of a device of this character by means of which 50 securing of the ends of the new strip of elastic may be effected without any necessity for stitching, thereby avoiding considerable expenditure of time, labor and preventing annoyance.

An additional object is the provision of a 55 device of this character which will be simple and inexpensive in manufacture, highly ef-

ficient and durable in use, and a general improvement in the art.

With the above and other objects and advantages in view, the invention consists in the details of construction to be hereinafter more fully described and claimed, and illustrated in the accompanying drawings in which:

Figure 1 is a side elevation of one of the 65 elements in opened-up or initial condition,

Figure 2 is a similar view of the coacting element;

Figure 3 is an elevation showing both 70 members applied to a strip of elastic and in interengaged condition,

Figure 4 is a detail section on the line 4—4 of Figure 3, and

Figure 5 is an edge view.

Referring more particularly to the drawings, the numerals 10 and 11 designate the two elements of my device, and both of these elements are constructed from some suitable thin resilient material, preferably metal of such nature as to be incapable of 80 corrosion. The member 10 is initially a flat body provided at one end with a substantially arrow shaped head 12 connected thereto by a constricted neck portion 13. At opposite sides of the body are prongs or tines 85 14 adapted to be bent upon the lines 15 as will be hereinafter explained.

The member 11 is also initially a flat piece or body formed at opposite sides of one end with prongs or tines 16 adapted to be bent 90 upon the lines 17 as will be explained. The other end of the member 11 is rounded as indicated at 18 and the intermediate portion is formed with an elongated slot 19 opening into a transverse slot 20. At the 95 junctures of the two slots, the corners are rounded off as indicated at 21.

In actual practice it is intended that a strip of elastic indicated at A be equipped with the two devices, one of which is mounted at each end. In order to effect securing of the member 10 upon one end of the elastic, the elastic is laid upon this member and the prongs or tines 14 are bent, clinched or crimped over upon the lines 15 so as to bitingly or penetratingly engage the elastic and effect positive securing of the device.

The member 11 is disposed against and secured to the other end of the elastic in substantially the same manner, the prongs or tines 16 being bent over upon the lines 17 and forced into penetrating or biting en-

gagement with the elastic. After both of the members have been applied, it is obvious that the elastic may be very easily threaded through the hem of a garment, either of the elements or members 10 or 11 being introduced first, it making practically no difference in view of the fact that they both have rounded ends. In this way it is evident that the use of a bodkin, safety pin or other make-shift device will be entirely avoided and the work of threading the elastic through greatly facilitated. After the elastic is in place, it is obvious that the ends may be secured in a very simple manner by inserting the arrow like head 12 through the slot 19, then moving the member 10 longitudinally with respect to the member 11 to bring the constricted neck portion 13 to the transverse slot 20, and then relatively turning the members so that the neck will engage within the transverse slot. When this is done the device will have the appearance disclosed in Figures 3 and 5, the members 10 and 11 overlying each other. In order to make the device conform more nearly to the curvature of the waist or limb of the wearer, it is preferable that the two members 10 and 11 be somewhat curved longitudinally as clearly indicated in Figure 5.

From the foregoing description and a study of the drawings it will be apparent that I have thus provided a simply constructed, inexpensive and efficient device for the purpose specified which will be a great

saver of labor and time and which will avoid annoyance. Owing to the simplicity of the parts it is evident that there is practically nothing to get out of order so that the device should have a long and satisfactory life.

While I have shown and described the preferred embodiment of the invention, it should be understood that I reserve the right to make such changes in the form, construction and arrangement of parts as will not depart from the spirit of the invention or the scope of the subjoined claim.

Having thus described the invention, I claim:

In a device of the character described, a pair of flat elongated body members each adapted for engagement upon the ends of a strip of flexible material and each having a plurality of prongs at its side edges adapted to be bent over and crimped upon the flexible material, one member having a substantially arrow shaped head connected with the body by a constricted neck portion and the other member having an elongated slot at its central portion opening out in to a transverse slot, the corners at the junctures of the slots being rounded, said arrow shaped head being adapted for insertion within the first named slot whereby the constricted neck may be turned and brought into the second named slot.

In testimony whereof I affix my signature.

FAY L. KUELLMER.
